United States Patent Office

Des. 198,451
Patented June 16, 1964

198,451

SOFA

Earl M. Slosberg, Philadelphia, Pa., assignor to Built-Rite Upholstery Co., Wallington, N.J.

Filed Dec. 13, 1962, Ser. No. 72,849

Term of patent 3½ years

(Cl. D15—11)

Fig. 1

FIG. 2

FIG. 3

The side not shown is the same in appearance as the side shown.

I claim:

The ornamental design for a sofa, substantially as shown and described.
